CLAIM

We claim the ornamental design for an audio device with display, as shown and described.

DESCRIPTION

FIG. 1 is a front perspective view of an audio device with display showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is an enlarged view of the encircled portion in FIG. 3;

FIG. 10 is an enlarged view of the encircled portion in FIG. 6; and,

FIG. 11 is an enlarged view of the encircled portion in FIG. 8.

The evenly-dashed broken lines in the figures depict portions of the audio device with display which form no part of the claimed design.

The dot-dash broken lines in the figures represent boundaries of the claimed design and form no part thereof.

(Continued)

The dot-dot-dash broken lines encircling portions of the audio device with display design shown in enlargements form no part of the claimed design.

1 Claim, 10 Drawing Sheets
